John Diederich.

ATTORNEY.

UNITED STATES PATENT OFFICE.

HENRY CLAY, OF PHILADELPHIA, PENNSYLVANIA.

SWITCH-BOARD FOR TELEPHONES.

SPECIFICATION forming part of Letters Patent No. 280,351, dated July 3, 1883.

Application filed September 21, 1882. (No model.)

To all whom it may concern:

Be it known that I, HENRY CLAY, a citizen of the United States, residing in the city and county of Philadelphia, State of Pennsylvania, have invented a new and useful Improvement 5 in Switch-Boards for Telephones, which improvement is fully set forth in the following specification and accompanying drawings, in which—

10 Figure 1 is a side elevation and partial section of the switch-board embodying my invention. Figs. 2 and 3 are top views of the parts thereof. Fig. 4 is an end view of Fig. 3.

15 Similar letters of reference indicate corresponding parts in the several figures.

My invention consists of certain improvements in switch-boards for telephone-exchanges, the construction, operation, and advantages being hereinafter fully set forth.

20 Referring to the drawings, A represents a perforated metallic plate in electrical connection with the telephone at the central office, and B represents a magnet which is properly supported on a base, B', with which the plate 25 A is attached.

C represents an armature for the electromagnet B. This armature is mounted on the base B', and two catches, D D, are pivoted to it at the end opposite to said magnet. Two 30 levers, E E, are pivoted to the said base, and are arranged to abut, respectively, against the said catches D D when in normal position. This position is upright, as shown in the drawings; but a horizontal or inclined arrangement 35 may be adopted instead. Said levers are provided with springs or weights for holding each of them in said normal position, and they are insulated from said catches at the points of contact. They are also insulated from each 40 other by the base B', which is a non-conductor of electricity.

F represents the line-wires which lead to the different subscribing-stations, each wire depending from the plate A through one of the 45 perforations thereof, and having at top a metallic piece, G, which is held in contact with the wall of the perforations of the plate A, the wire having an attached weight, H, or being otherwise weighted to insure the contact of the 50 piece G and plate A. The top of each wire terminates in an eye, J, which, when the wire

is raised, may be fitted on either of the two levers E, and to each wire, between said eye and the piece G, is secured an insulating-plug, K, whereby the wires may be handled and operated with safety. 55

To complete the circuit, a wire extends, as shown, from ground 1 to the telephonic apparatus or instrument of the subscriber on line 31. The circuit is then through said ground 60 1, instrument on line 31, the line-wire F³¹ of the said instrument, plate A, thence through a wire to central-office telephone, and thence through a wire to ground 2.

The operation is as follows: When subscriber 65 No. 31 wishes to communicate with some other subscriber, he first removes his telephone from its hook, which forms part of the signaling-instrument, separately applied for. As described in that application, this removal allows the 70 mechanism of said signaling-instrument to close the circuit with the central office through the connections above described. After the central office learns the requisition from subscriber No. 31, the operator takes the eye J³¹ of line-wire F³¹, and attaches it to lever E. In so doing, the eye J³¹ is necessarily brought into electrical contact with the catch D for said lever, and lifts said catch. As this catch is in metallic connection with the generator by means 80 of wire C', a momentary circuit is established through the telephone of subscriber 31, and this produces a gurgling noise, which notifies him that his requisition is attended to. The wire F and eye J of the subscriber who is 85 called for are then manipulated in like manner, and when said metallic eye raises the catch D, with which it comes in contact, it completes a momentary circuit for said subscriber's notification through said catch and 90 connections, like those above described, except that the signaling-instrument and not the telephone of the latter subscriber is in said circuit. The 95

He will then be notified by the sounding of his bell. Both the eye J³¹ of the first-named subscriber and the eye J³⁷ of the latter subscriber (see Fig. 1 for latter eye) are by this time in electrical contact with their respective levers E, on which they are hung. The instrument 37 of this latter subscriber of course 100 has ground-connections and line-wire connections similar to those of instrument 31. The

circuit is then from ground of instrument 31 through its ground-wire, said instrument, line-wire F³¹, eye J³¹, lever E, through wire to magnet B, from magnet B through wire to the other 5 lever on which eye J³¹ is hung, thence through said eye and the line-wire F³¹, through the instrument of subscriber 37 and its ground-wire to ground. When the parties 31 and 37 have finished talking, the telephones of their 10 instruments are hung upon the respective hooks of their call-bells or signaling apparatus, which causes the mechanism of the latter to be set in motion. This generates a current of electricity, as described in my separate application for said call-bell mechanism, and this current (which follows the circuit last described) is of sufficient strength to magnetize the cores 15 of magnet B and attract armature C, thereby raising the catches D from the levers E. The weights H of the respective telephone wires F will then cause the said levers to turn outwardly until the eyes J drop off from them, thus breaking the circuit. The springs or 20 weights of said levers then return them to their normal position, and the catches D fall again by their own weight (the armature being no longer attracted) into the position 25 shown in Fig. 1.

Having thus described my invention, what I claim as new, and desire to secure by Letters 30 Patent, is—

1. The perforated metallic plate in electrical connection with the central-office telephone, in combination with catches D and gravitating wires, which are held in contact with said plate 35 when not in use, and adapted to be moved to form a circuit through said catches and the central-office generator while placing different subscribers in communication.

2. The perforated metallic plate connected 40 with the central-office telephone, in combination with the wires having metallic pieces G, substantially as and for the purpose set forth.

3. The combination of the line-wires having 45 the eyes J, with the levers E and perforated plate, substantially as set forth.

4. The magnet B, in combination with the armature C, having catches D, and the levers E, the magnet being included in a circuit between said levers, substantially as and for the 50 purpose set forth.

5. The perforated plate, in combination with the wires having metallic pieces G, eyes J, and insulating-plugs K, substantially as and for the purpose set forth.

HENRY CLAY.
